FIG. 10

FIG. 11

FIG. 1 is a front, top and right side perspective view of a microfiche viewer showing one form of my new design wherein the viewing screen is of substantially the same width as, and centered above, the base;

FIG. 2 is a front elevational view of the viewer of FIG. 1.

FIG. 3 is a left side elevational view of the viewer of FIG. 1.

FIG. 4 is a right side elevational view of the viewer of FIG. 1.

FIG. 5 is a rear elevational view of the viewer of FIG. 1.

FIG. 6 is a top plan view of the viewer of FIG. 1.

FIG. 7 is a front, top and right side perspective view of a microfiche viewer showing a second form of my new design wherein the viewing screen is substantially wider than, and extends substantially equal distances beyond, the base;

FIG. 8 is a front elevational view of the viewer of FIG. 7.

FIG. 9 is a rear elevational view of the viewer of FIG. 7.

FIG. 10 is a top plan view of the viewer of FIG. 7.

FIG. 11 is a sectional view taken along the line 11—11 of FIG. 5.

The left and right side elevational views and sectional view of the viewer of FIG. 7 are the same as shown in FIGS. 3, 4 and 11, respectively.

The essential features of my design reside in the portions shown in solid lines on the drawings.

I claim:

The ornamental design for a microfiche viewer, as shown and described.
